UNITED STATES PATENT OFFICE.

POWEL CROSLEY, JR., OF CINCINNATI, OHIO.

CONDENSER.

Application filed May 23, 1921. Serial No. 471,806.

To all whom it may concern:

Be it known that I, POWEL CROSLEY, Jr., a citizen of the United States, residing at Cincinnati, in the county of Hamilton and State of Ohio, have invented certain new and useful Improvements in Condensers, of which the following is a specification.

My invention relates to improvements in electrical condensers, especially those where-
10 in it is desired to vary the capacity readily, such, for instance, as are used in radio communication.

The object of my invention is to provide very simple construction for such devices, especially in the means for varying the capacity, and yet have the device durable and accurate in its operation. A further object is to make the capacity variation more uniform in the earlier stages of reduction from 20 its maximum capacity. Other objects will appear in the course of the ensuing description.

I attain these objects by the device illus-
25 trated, for example, in the accompanying drawing, in which—

Figure 1 is a plan view of the condenser in its closed condition of maximum capacity;

Fig. 2 is a side elevation of the same;

Fig. 3 is a rear elevation of the same; and

Fig. 4 is a plan view, similar to Fig. 1, showing a modification.

As herein shown in Figs. 1, 2 and 3, there is a base or bracket 1 made of insulating material, preferably a material permitting the part to be molded in its required shape, such as fiber or resinous composition much used for forming insulating bodies in electrical work. This base 1 comprises the main body part 2 extending backward and being of a length and up and down width sufficient to afford the required area, and of a thickness to afford the required rigidity when made of some such material as mentioned. At its front end, this body 2 has the front leg 3 extending across therefrom at right angles thereto, throughout its up and down width. The side of the body 2 remote from the leg 3 has the recess 4 throughout its interior, leaving only a flange 5 around the four edges, for lightness and

strength. A boss 6 projects back a short distance from the leg 3, midway of the height of the body 2 and leg 3, and continuous over to the junction of these portions of the base, thereby strengthening it, and also avoiding any undercut, facilitating molding of the base. At the top and the bottom of the junction of these parts 2 and 3 are ears 7 and 8, respectively, projecting diagonally across from the outer edge of the leg 3 to a distance well back of the rear side of the boss 6. These ears 7 and 8 also reinforce the structure of this base 1 at the junction of its parts 2 and 3; and their adjacent sides are outside the upper and lower limits of the body part 2, leaving the entire side of this part next to the leg 3 unobstructed, from the boss 6 to the rear end of the part 2, which side is flat, forming as nearly as possible a perfect plane 70 surface. The front side of the leg 3 is flat, to lie against the wall 9, which will be understood to be the front wall of a cabinet or the like, in which the condensers usually are mounted for use.

Mounted on the flat side of the body part 2 of this base is a thin plate or sheet of conducting material 10, preferably a very thin sheet of copper. Such material may be secured to the insulating base part 2 by any suitable means, preferably by a suitable cementing material, or a glue. This sheet 10 has an integral tongue 11 near its lower edge, projecting from its rear edge and bent around the rear end of the part 2 of the insulating base 1, and a binding screw 12 passes through this tongue 11, being tapped into the insulating base 1 and serving to connect the conductor 13 to the sheet 10 by clamping this conductor and the tongue 11 against the end of the base 1. This sheet 10 of conducting material is of substantially the full up and down width of the flat side of the base part 2, and extends substantially to the rear end thereof. Its front edge may be some distance back from the junction of the parts 2 and 3, according to circumstances later to be described.

The movable member 14 also is of insulating material, preferably the same kind as 100

that composing the base 1, molded into its required shape. It is of about the same general thickness as the body 2 of the base 1, and of the up and down width thereof, with 5 its front edge 15 rounded to clear the junction of the boss 6 with the base part 2 when this member 14 is brought very close to the part 2. Its side to lie next to the part 2 is flat, and as nearly as possible a perfect plane 10 surface; but its opposite side preferably has a central rectangular boss 16 with ribs 17 running to the respective rear corners of the member, and ribs 18 running to hinge bosses 19 at respective front corners of the member, from this central boss 16. Also, 15 preferably, this boss 16 has a central rectangular recess 20; the boss 16 and recess 20 being of greatest length up and down. A plate 21 of suitable wearing material, as 20 steel, is secured in this recess 20 with its face flush with the face of the boss 16.

Mounted on the flat side of the movable member 14 is a thin plate or sheet of conducting material 22, preferably of the same 25 material as that of the sheet 10 that is mounted on the flat surface of the base part 2, as very thin sheet copper. It may be secured to the member 14 in any suitable manner, preferably the same as with the sheet 10. 30 as with cementing material, glue or the like. This sheet 22 has an integral tongue 23 near its upper edge, projecting from its rear edge and bent around the rear end of the member 14, with a binding screw 35 24 through it and tapped into the member 14, connecting the conductor 25 to the sheet 22 by clamping this conductor and the tongue 23 against the rear end of the member 14. This sheet 22 of conducting material 40 is of substantially the full width up and down as the flat side of the member 14, and extends substantially to the rear end thereof. Its front edge is about coincident with that of the sheet 10 that is on the base part 2 when 45 the member 14 is assembled with the base 1; these flat adjacent sides of the member 14 and part 2 being of substantially the same dimensions up and down.

Hinge pins 26 pass through the ears 7 and 50 8, respectively down into and up into the hinge lugs or bosses 19 of the member 14, thus connecting the member 14 to the base 1 to have its rear end about coincident with the rear end of the base part 2 when the 55 member is swung closest to the part 2. Springs 27, each comprising a middle loop 28 around a respective projecting hinge pin 26 and a member 29 projected diagonally forward and hooked into a hole 30 in the top or 60 bottom, as the case may be, of the base leg 3, and a member 31 projected backward and hooked into holes 32 in edges of the member 14, act to hold the member 14 away from the part 2 of the base 1 in the absence 65 of any restraining means; the normal con-

dition of the spring 27 being one with its members 29 and 31 approached to each other. These springs 27 are held on the device by having their hook parts fitting with sufficient tightness in the holes 30 and 70 32; or the pins 26 may have heads 33 and fit tightly in either the ears 7 and 8 or the member 14, these heads 33 retaining the springs by engaging their loops 28; or both of these provisions may be relied upon, as 75 indicated in the drawings.

Mounted upon one of the sheets 10 or 22 of conducting material, preferably on the conducting sheet 10 on the insulating base 1, is a very thin sheet of dielectric material 80 34, such as mica. This sheet 34 is of ample dimensions to completely separate the conducting sheets 10 and 22 electrically throughout their area, as required in a condenser. It is secured to the conducting sheet, as the sheet 10 as here shown, by any suitable means, preferably by a suitable cementing material, or a glue.

In the drawing, for purpose of clearness, the conducting sheets 10 and 22, and this dielectric sheet 34, are shown as of considerable thickness; but actually, the dielectric sheet, such as mica, is extremely thin, for instance, two one-thousandths of an inch in thickness; and the sheets of conducting material also are preferably very thin, for instance about one one-hundredth of an inch in thickness. It will be understood that for maximum capacity, the two conducting surfaces of the sheets 10 and 22 are to be as close together as possible without actually making an electrically conducting communication; and the dielectric sheet 34, while adding to the capacity by its superior dielectric properties compared with air, must be thin enough to permit the maximum-capacity closeness of the two conducting surfaces. For the same reason, the surfaces are made as nearly perfectly plane as is commercially practicable, so as to have this closeness of the conducting surfaces as nearly as possible uniform throughout their area. For this reason, I prefer a material easily molded with very true surfaces, and not liable to warp in use; such as the molded compositions referred to.

The cam shaft 35 extends rearwardly through a journal bearing in the leg 3 and the boss 6 thereof, preferably having a bushing 36 of wearing material, as steel, around it in this bearing. This bushing may project somewhat rearwardly from the boss 6, adding to the rigid bearing area for the shaft 35. The rear end of the shaft 35 is reduced, leaving a shoulder, and the cam 37 fits tightly on this reduced part and the shaft end is riveted tightly against the cam, holding the cam to turn with the shaft. This cam, as here shown, is merely a circular disk, with the shaft 35 fastened in it a 130

proper distance from the center of the disk to afford an eccentric action with the edge of the disk against the bearing plate 21 of the movable member 14. When the disk is rotated over toward the parts 14 and 2, it forces the member 14 toward the part 2, wedging its greatest radius against the member 14 and clamping the conducting sheet 22 tight against the dielectric sheet 34 on the base 1, as seen in Fig. 3 most clearly. The condenser will then have its maximum capacity. Rotating the shaft 35 to swing this cam 37 away from the parts 14 and 2 releases the member 14 to be swung away from part 2 by the springs 27, reducing the capacity of the condenser.

The cam shaft 35 extends forward through an opening 38 in the cabinet wall 9, and has a suitable knob 39 fixed on it, with a dial 20 40 moving past a pointer 41 on the cabinet front, as well known in devices of the character in which condensers are used. A pin 42 through the cam-shaft 35 back of the bushing 36, with a washer 43 between it and the 25 bushing, prevents end play.

In Fig. 4 is a condenser of practically the same nature as that just described, but with the details of construction more adapted for making the base and movable member of wood or the like. The base 1' is made up of a body piece 2' having its front edge suitably joined, as by gluing, to the front leg piece 3' near one up and down edge thereof. Preferably, in making this joint, a strip of flexible material, such as textile fabric, is interposed in the joint and held therein by the same means, as the glue, that attaches the pieces 2' and 3' together. This material thus is adapted to form a hinge 26' for the movable member 14', which has its front edge 15' beveled in toward the joint of the pieces 2' and 3' to swing on the flexible hinge 26' close to this joint. In this figure, the thicknesses of conducting and dielectric sheets are exaggerated as in the previous illustration; and it will be understood that this hinge 15' will swing very close to the joint in actuality. The bearing plate 21' is fixed on the outer surface of the member 14', and the cam 37 bears thereon as in the other example. Also, the connections of the conducting sheets to the conductors are the same, with like reference numerals; and the bearing bushing 36' of the cam shaft 35' is fixed in the front leg piece 3' in a manner similar to the other example. A spring 42', coiled around the shaft, has one end in the hole in the shaft, so that when the device is assembled with the front knob on the shaft 35, the dial 40 will hold at any position. In the other example, friction of the cam on the member 14, against the pressure of the springs 27, is relied upon to hold the parts in adjusted positions. of either example herein shown may be varied or interchanged as conditions may call for. Therefore, while certain constructional details are deemed preferable in connection with my invention, and I have shown and described these rather specifically in elucidating the construction and use of my invention, as is required, I do not wish to be understood as being limited to such precise showing and description, but having thus fully described my invention,

What I claim as new and desire to secure by Letters Patent is:

1. In a condenser, a plurality of elements having opposed dielectrically separated electrically conducting surfaces, a support on which one of said elements may be moved toward or away from the other element, to vary the capacity between said surfaces, manipulating means, and operating means having a sliding engagement with said one of said elements to transmit movement of the manipulating means to said one of said elements, this one of said elements yieldingly resisting said operating means, whereby the element and the operating means have their sliding engagement maintained throughout the movement.

2. In a condenser, a plurality of elements having opposed dielectrically separated electrically conducting surfaces, a support on which one of said elements may be moved into or out of substantial parallelism with the other element, to vary the capacity between said surfaces, manipulating means and operating means having a sliding engagement with said one of said elements to transmit movement of the manipulating means to said one of said elements.

3. In a condenser, a plurality of elements having opposed dielectrically separated electrically conducting surfaces, a support on which one of said elements may be moved into or out of substantial parallelism with the other element, to vary the capacity between said surfaces, manipulating means, and operating means having a sliding engagement with said one of said elements to transmit movement of the manipulating means to said one of said elements, this one of said elements yieldingly resisting said operating means, whereby the element and the operating means have their sliding engagement maintained throughout the movement.

4. In a condenser, a plurality of elements having opposed dielectrically separated electrically conducting surfaces, one of said elements being movable toward or away from the other element, to vary the capacity between said surfaces, manipulating means, rotary operating means turned by said manipulating means, having an actuating surface eccentric to its rotation, and means holding said one of said elements toward this actuating surface, whereby said operating means sustains

this element at various distances from its center of rotation and at complementary distances from the other element, upon rotation of said operating means by said manipulating means, whereby inaccuracy of adjustment of said manipulating means is minimized in the adjustment of this element relatively to the other element.

5. In a condenser, a plurality of elements having opposed dielectrically separated electrically conducting surfaces, a support on which one of said elements may be moved into or out of substantial parallelism with the other element, to vary the capacity between said surfaces, manipulating means, rotary operating means turned by said manipulating means, having an actuating surface eccentric to its rotation, and means holding said one of said elements toward this actuating surface, whereby said operating means sustains this element at various distances from its center of rotation and at various angles of divergence from the other element, upon rotation of said operating means by said manipulating means, whereby inaccuracy of adjustment of said manipulating means is minimized in adjusting the angular relation of said elements.

6. In a condenser, an electrically-insulating base comprising a body having a flat side and a leg projecting from one end of said body, past said flat side, a metal sheet secured to and extending across said flat side, an electrically-insulating member having a flat side opposed to said flat side of said base, and being hinged to said base near the junction of said leg and said body, whereby said member may swing its flat side substantially parallel with or divergent from said flat side of said base, a metal sheet secured to and extending across said flat side of said member, a dielectric element interposed between said metal sheets, means for making electrical connections with the respective metal sheets, a cam shaft journaled in said leg and projecting along the other side of said member, a cam fixed on said shaft and engaging with said other side of said member, and yielding means pressing said member toward said cam.

7. In a condenser, a plurality of elements having opposed dielectrically separated electrically conducting surfaces, a support on which one of said elements may be moved to vary the spacing between this element and the other element, to vary the capacity between said surfaces, manipulating means, and operating means transmitting the motion of the manipulating means to said one of said elements, whereby, with a constant rate of movement of said manipulating means, said one of said elements is moved at a decreasing rate as it is made to approach said other element.

8. In a condenser, a plurality of elements having opposed dielectrically separated electrically conducting surfaces, a support on which one of said elements may be moved to vary the spacing between this element and the other element, to vary the capacity between said surfaces, manipulating means, and operating means transmitting an harmonic motion to said one of said elements as derived from a motion of constant rate imparted to said manipulating means, the decrease in the harmonic motion progressing as the one element approaches the other element. 10

POWELL CROSLEY, JR.
